OPHTHALMIC BRUSH

Nelson E. Abrahamsen, Cleveland, Ohio

Application March 11, 1954, Serial No. 29,477

Term of patent 14 years

(Cl. D9—2)

Fig. 1

Fig. 2

Fig. 3

To all whom it may concern:

Be it known that I, Nelson E. Abrahamsen, have invented a new, original, and ornamental Design for an Ophthalmic Brush, of which the following is a specification, reference being had to the accompanying drawing, forming a part hereof.

Figure 1 is a top plan view of an ophthalmic brush, showing my new design;

Figure 2 is a side elevational view thereof; and

Figure 3 is a bottom plan view thereof.

I claim:

The ornamental design for an ophthalmic brush, substantially as shown.
